UNITED STATES PATENT OFFICE.

FRED O. RUSH, OF WILMINGTON, DELAWARE.

DIPPER-TOOTH FOR EXCAVATING-MACHINES.

1,131,426.

Specification of Letters Patent.

Patented Mar. 9, 1915.

Application filed August 20, 1912. Serial No. 716,008.

To all whom it may concern:

Be it known that I, FRED O. RUSH, a citizen of the United States, residing at Wilmington, in the county of New Castle and State of Delaware, have invented certain new and useful Improvements in Dipper-Teeth for Excavating-Machines, of which the following is a specification.

My invention relates to improvements in dipper teeth for excavating machines, and has for its primary object the provision of a tooth of this character in which the cutting point or tip may be renewed from time to time as it becomes worn or broken, without the necessity of discarding the entire tooth.

Another object of the invention is to provide means for securing such a removable cutting point or tip rigidly to the body portion of the tooth and holding the same against all movement relatively thereto.

A further object of the invention is to provide a detachable cutting tip which will be capable of being reversed to afford a double cutting edge, thus prolonging the life and increasing the usefulness of the tip.

To attain the desired objects, the invention broadly stated consists of a tooth composed of three parts, a base or body portion for attachment to the bucket or dipper of the excavator, a tip holder secured to said basal portion, and a tip secured to said tip holder, the invention further consisting in certain novel features of construction and adaptation of parts, substantially as shown, described, and claimed hereinafter.

Figure 1 is a side elevation of a dipper tooth constructed in accordance with and embodying the principles of my invention. Fig. 2 is a top plan view thereof. Fig. 3 is a section on lines 3—3 of Fig. 1. Fig. 4 is a section on line 4—4 of Fig. 1, and Fig. 5 is a section on line 5—5 of Fig. 1.

In the drawings:—The letter A designates the body portion or base of the tooth, which may be formed of any suitable material, and as the same is subjected to comparatively little wear, this material need not be of the same high quality as that required for the cutting point. This body portion is provided at its rear end with a longitudinal slot B, adapted to engage the front wall of the dipper, thus dividing the body portion into two portions or shanks C and D. These shanks may be of any suitable thickness and length relatively one to

the other and to the front wall of the dipper, but inasmuch as the greatest strain and wear comes upon the shank C which is located on the inner face of the dipper front, this shank is preferably constructed of heavier material than the shank D and is here shown as greater in length than the shank D. This construction permits the tooth as a whole to be adapted to any size or type of dipper in use, said shanks being secured to the dipper by means of suitable bolts or rivets passing through holes K therein.

The extreme forward end of the body portion is cut away or rabbeted to form a reduced portion E, which is received in a recess with a concave rear wall formed in the tip holder G, detachably secured to said body portion by the bolt H passing vertically therethrough.

The tip or cutting point J is detachably secured to the tip holder by means of a soft steel pin K passing transversely through a hole L in the tip holder, said pin being slightly chamfered to hold it in place. All strain on this pin is taken up by the lugs M formed on the tip and seated in recesses N in the tip holder.

It will thus be seen that the tip holder can be made to fit any base now in use, and that the base can be adapted to any type of dipper, while the cutting point or tip is reversible and therefore has double the life of the ordinary cutting point. The tip is particularly adapted for use upon types of teeth known as the "Marion" and "Panama," and can be used upon any two part tooth or solid tooth as well.

It will thus be seen that I have provided a tooth for excavating dippers and the like, the cutting point of which can be renewed as frequently as it becomes worn or broken, without the necessity of discarding or renewing the body portion. This construction enables me to make the cutting point of the tooth, which receives the largest part of the wear and strain, of a very high grade of material, while the body portion of the tooth may be of an inferior grade of material, if desired, thereby reducing the cost of manufacture and effecting a material saving not only in the body portion of the tooth, but in the tip as well, as this tip can be reversed and when worn upon both cutting edges, be renewed without discarding the body portion thereof. It will also be

seen that the cutting point of tip is so mounted as to be held against all movement relatively to the body portion, thus providing a tooth which is practically integral therewith and possesses all the qualities of such a tooth without having any of its disadvantages.

The tooth it will be noted is made of sections fitted together and the advantage of this resides in the fact that should a section become worn or broken, a new section can be furnished and at a small cost, making it unnecessary to supply a new tooth at a great expense and difficulty.

15 I claim:—

1. A dipper tooth, comprising a body portion having a tapered nose and at its rear end a longitudinal slot adapted to engage the front wall of a dipper providing oppositely disposed shanks, said shanks being of different lengths, a tip holder having a tapered recess for receiving the nose of said body portion, means passing transversely through said holder and shanks and traversing said slot, and a reversible tip detachably connected with said holder, said tip and tip holder having recesses and ribs

- 25

forming interengaging means for taking the strain from the connecting pin of said tip.

2. A dipper tooth, comprising a body portion having a tapered nose and at its rear end a longitudinal slot adapted to engage the front wall of a dipper, providing oppositely disposed shanks, said shanks being of different lengths, a tip holder having a tapered recess for receiving the nose of said body portion, means passing transversely through said holder and shanks and traversing said slot, and a reversible tip having a tapered nose portion and an inner curved end detachably connected with said holder, said tip and tip holder having recesses and ribs forming inter-engaging means for taking the strain from the connecting pin of said tip, said pin passing transversely through the tip and holder.

In testimony whereof I affix my signature in presence of two witnesses.

FRED O. RUSH.
